UNITED STATES PATENT OFFICE

157,473

SPRAY GUN FRAME

John F. Engler, Houston, Tex.

Application February 10, 1948, Serial No. 144,387

Term of patent 3½ years

(Cl. D62—2)

To all whom it may concern:

Be it known that I, John F. Engler, a citizen of the United States, residing at Houston, in the county of Harris, in the State of Texas, have invented a new, original, and ornamental Design for a Spray Gun Frame, of which the following is a specification, reference being had to the accompanying drawing, forming a part thereof.

Figure 1 is a side elevational view of a spray gun frame embodying my new design.

Figure 2 is a top plan, and

Figure 3 is a nozzle end view thereof.

I claim:

The ornamental design for a spray gun frame, as shown.

JOHN F. ENGLER.
